Augustus B. Stoughton
ATTORNEY.

UNITED STATES PATENT OFFICE

GEORGE W. HAUSE, OF PHILADELPHIA, PENNSYLVANIA

GAME APPARATUS

Application filed November 7, 1930. Serial No. 493,932.

The principal objects of the present invention are, first, to provide a single fairway or ball-path with a plurality of hazards or obstructions which may be brought upon the fairway in succession. Second, to provide a game apparatus which, when used as a miniature golf course, gives the effect of an 18 or other multiple hole course although there is but a single fairway or ball-path. Another object of the invention is to provide a game apparatus of the character mentioned which occupies but comparatively small space in comparison with the variety of hazards or obstructions which it presents.

The invention comprises the improvements to be presently described and finally claimed and generally stated it may be said to consist of a fairway or ball-path having at one end a ball cup and affording at the other end an opportunity to play balls along it and having intermediate of its ends a crosswise movable carrier adapted in its movement to present on the fairway or ball path different hazards or obstructions.

The invention also comprises the improvements to be presently described and finally claimed. In the following description reference will be made to the accompanying drawing forming part hereof and in which,

Figure 1 is a top or plan view of game apparatus embodying features of the invention.

Figure 2 is a transverse sectional view taken on the line 2-2 of Figure 1.

Figure 3 is a sectional view drawn to an enlarged scale and taken on the line 3-3 of Figure 1, and

Figure 4 is a side elevation of a portion of the apparatus.

In the drawing,
1 is a fairway or ball-path and it is shown
as provided with an upstanding marginal
rim 2. At one end of the fairway or ball-
path there is arranged a cup 3 and the por-
tion of the upstanding rim adjacent the cup
is of curved form and need not be concen-
tric with the cup. Balls are played from
the opposite end of the fairway or ball-path
59 from which the rim 2 is omitted and if de-

sired use may be made of rubber or other tees 4 for that purpose. If desired, the curved portion of the rim 2 may be lined with a rubber cushion 5 and the rim of the cup 3 may be also covered with a rubber cushion 6 and fitted with a rubber hemisphere 7. 55 8 is a carrier movable crosswise of the fairway or ball-path and it is arranged between the ends of the same. The carrier 8 is provided with a number of hazards of which three, 9, 10 and 11, are shown but of which the number may be increased or diminished as desired. Intermittent motion is imparted to the carrier 8 so that each of the hazards can be brought onto the fairway or ball-path and permitted to remain there as long as may be necessary to suit the convenience of the players. As shown, use is made of square revolvable bodies 13 and 14 for moving the carrier through the action of pins 15 60 on the body and apertures 16 in the carrier for the reception of the pin. A crank 12, accessible to the player, is shown as a means for moving the carrier and there is a detent 17 which by taking into openings 18 in the part 14 holds the carrier at rest. The detent is released by handle 19 accessible to the 65 players and operating through a link 20. 70 75

It will be obvious to those skilled in the art that modifications may be made in details of construction and arrangement without departing from the spirit of the invention which is not limited to such matters or to matters of mere form or otherwise than the appended claims and the prior art may require. 85

I claim:

1. A game apparatus comprising a ball-path, an upstanding rim surrounding said ball-path, a cup adjacent one end of said ball-path, a carrier movable crosswise of said ball-path and forming a portion of the surface of said ball-path, and a plurality of hazards mounted on said carrier and movable thereon so as to be presented in succession on the ball-path. 95

2. A game apparatus comprising a ball-path, a carrier movable crosswise of the ball-path and forming a portion of the surface of the ball-path, and a plurality of hazards 165

mounted on said carrier and movable to be presented in succession on the ball-path.

3. A game apparatus comprising a ball-path, a carrier movable crosswise of the ball-path and forming a portion of the surface of the ball-path, a plurality of hazards mounted upon said carrier so as to be presented in succession on said ball-path, and means accessible at one end of the ball-path for moving said carrier.

10 4. A game apparatus comprising a ball-path, a carrier movable crosswise of the ball-path, and forming a portion of the surface of said ball-path, a plurality of hazards mounted upon said carrier and movable so as to be presented in succession on said ball-path, means accessible at one end of the ball-path for moving said carrier, and second means accessible from one end of the ball-path for positioning the carrier.

15 5. A game apparatus comprising a ball-path having at one end a plane position, a rim substantially surrounding said ball-path except at said plane position, a cup located adjacent the opposite end of said ball-path from said plane position, tees of flexible material at said plane position, a carrier movable crosswise of the ball-path and forming a portion of the surface of the ball-path, and a plurality of hazards mounted upon said carrier and movable so as to be presented in succession on the ball-path.

GEORGE W. HAUSE.
